CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; FIG. 2 is another embodiment thereof; FIG. 3 is another embodiment thereof; FIG. 4 is another embodiment thereof; FIG. 5 is another embodiment thereof; FIG. 6 is another embodiment thereof; FIG. 7 is another embodiment thereof; FIG. 8 is another embodiment thereof; FIG. 9 is another embodiment thereof; FIG. 10 is another embodiment thereof; FIG. 11 is another embodiment thereof; and, FIG. 12 is another embodiment thereof.

The broken lines in the figures show a display screen or portion thereof, and form no part of the claimed design.
